UNITED STATES PATENT OFFICE

2,520,910

VACUUM JET MANIFOLD

Fred P. Chadsey, Fillmore, Calif.

Application July 15, 1943, Serial No. 494,821

3 Claims. (Cl. 244—134)

1

2

My invention relates to improvements in elevators 4, tail stabilizers 5, and vertical fin 6, vacuum jet manifolds for distributing air, or gas, or the primary object in view being to provide a nacelles, as at 7, at the leading edge thereof, and simple form of manifold which is operative primarily by vacuum and adapted for a wide variety of uses, and principally as de-icing equipment for aeroplanes.

Other and subordinate objects are also comprehended by my invention, all of which, together with the precise nature of my improvements, will be readily understood when the succeeding description and claims are read with reference to the drawings accompanying and forming part of this specification.

In said drawings:

Figure 1 is a view in top plan, partly broken away and shown in section, of a preferred embodiment of my improved manifold and application thereof.

Figure 2 is a fragmentary view in side elevation drawn to an enlarged scale.

Figure 3 is a view in side elevation, partly in section, of the preferred embodiment of the manifold detached and drawn to a further enlarged scale.

Figure 4 is a view in top plan of the same.

Figure 5 is a fragmentary view in longitudinal section of the same.

Figure 6 is a view in longitudinal section taken on the line 6—6 of Figure 5.

Figure 7 is a detailed view in transverse section taken on the line 7—7 of Figure 5 and drawn to an enlarged scale.

Figure 8 is a fragmentary view in horizontal section taken on the line 8—8 of Figure 3 and drawn to an enlarged scale.

Figure 9 is a view in transverse section taken on the line 9—9 of Figure 8.

Figure 10 is a view in top plan of a modified embodiment of the manifold and application thereof, and

Figure 11 is a fragmentary view, partly in longitudinal section, of the modified embodiment of manifold.

Referring to the drawings by numerals, by way of exemplification of one use thereof, my improved manifold has been shown, in its preferred embodiment, as forming part of aeroplane de-icing equipment of the general type forming the subject matter of my co-pending application Serial No. 460,547, filed October 2, 1942, which became Patent No. 2,396,684, March 19, 1946, and to which attention is invited.

The aeroplane, as shown in Figures 1 and 2, comprises the fuselage 1, wings 2, rudder 3, tail

15 of hot exhaust gases from the motors over the wing as will be apparent to prevent ice from forming on the wing. The conduit 10 is arranged to heat the entire wing which it overlies, thus providing for de-icing of the entire wing area, including the leading edge. The design of the conduit 10 may be such as to conform in any suitable manner with the profile of the wing so that said conduit will not prevent the wing from functioning in the usual manner. In the drawings, the conduit 10 has been shown in a conventional manner for the purpose of illustration.

According to my invention in its preferred embodiment, a pair of manifolds 15 are provided upon each side of the fuselage 1, and are fixed to the fuselage in any suitable manner. Each manifold 15 comprises a transversely rectangular, tubular front section 16 extending over the wing 2 crosswise and having a closed front end suitably connected to the inner end of the conduit 9 in communication therewith, and a rear end nozzle portion 17 extended into a relatively larger, similarly shaped, tubular section 18 which, in turn, extends rearwardly from said nozzle portion 17 to within a short distance of the stabilizers 5 and opens thereon and onto the elevators 4. The nozzle portion 17 is centered in the section 18 to space the same from said section 18 and longitudinal fins 19 are provided around said nozzle portion 17 to space said portion and section apart and for another purpose presently seen. The rear section 18 is provided with a reduced tubular extension 20 projecting forwardly to the front of the aeroplane and for a purpose presently apparent. A pair of lateral branches 21, 22 connect the front section 16 with the inner ends of the channels 12, 14, respectively, and form, as will more clearly appear, an outlet

from said section 16 and an inlet thereinto. A 55 forwardly closing flap valve 23 is hinged, as at

24, at the inner end of the branch 21 to open into said section 16 and which is provided with a suitably operating lever 25. An upwardly and rearwardly inclined, auxiliary discharge branch 26 extends from the section 18 adjacent its rear end and is provided with a flap valve, as at 27, at its inner end, similar to the flap valve 23. A fan 28 is suitably mounted in the outer end of the branch 26 for operation by air and gas passing out of said branch to create a forced draft through said branch and out of the same.

Referring to the operation of the invention in the preferred embodiment and application thereof, as the aeroplane travels forwardly, the section 20 acts as an air scoop forcing atmospheric air into the section 18 and past the nozzle portion 17 through the space between said portion and the section 18. This creates a vacuum at the open end of the nozzle portion 17 and pressure rearwardly of said portion. The vacuum tends to create suction in the section 16 whereby hot exhaust gases from the motors are drawn from the conduit 9 into and through the section 16 to be discharged by the pressure in the section 18 out of the rear end of said section and also out of the branch 26. By partially opening the flap valve 23, as shown in full lines in Figure 8, the hot gases may be bypassed from the section 16, out of the branch 21, into the channel 12 to return to said section 16 by way of the channel 14 and under the suction present in the section 16. Thus the appropriate wing 2 may be heated to de-ice the same. By closing the flap valve 27, the hot gases discharged from the nozzle portion 17 may be directed, under the pressure in the section 18, out of said section and past the stabilizers 5, rudders 3 and elevators 4 and the fin 6 to prevent ice from forming on the same. As will be understood, the device is designed so that the volume of atmospheric air entering the same is insufficient to cool the hot gases in the section 18 to a degree rendering the same ineffective as a de-icing agent. By closing the flap valve 23 and opening the flap valve 27, the hot gases from the conduit 9 may be discharged into the atmosphere out of the branch 26, as when de-icing is not required. The fan 28 operates to create a boosting suction in the sections 16, 18.

If desired the exhaust pipes 8 may be provided with flap valves 8a adapted for opening to the atmosphere by connections, indicated in dotted lines at 8b, to operating hand wheels 8c all for the purpose of controlling the passage of hot gases from the exhaust pipes 8 to the manifold as, for instance, by cutting out any desired exhaust pipe or varying the volume issuing therefrom.

In the case of an aeroplane having a single motor 29 in the nose thereof, as shown in Figure 10, the front section 30 of the manifold may be directly connected at its front end to an exhaust pipe 31 of the motor 29 instead of to a conduit such as 9. In Figure 10, the wing 32 is provided therein with channels 33, 34 similar to channels 12, 14 and discharge and inlet branches 35, 36 extend from said section 30 and communicate with said channels 33, 34, respectively. Otherwise the construction and operation is the same as that described with reference to the preferred embodiment of the invention.

The foregoing will, it is believed, suffice to impart a clear understanding of my invention without further explanation.

Since my invention is susceptible of modification and adapted for other uses than those de-

scribed, without departing from the inventive concept, the present disclosure is to be construed as illustrative only, and right is herein reserved to modifications falling within the scope of the appended claims.

What I claim is:

1. The combination with a motor powered airplane having a fuselage and wings, of a pair of longitudinal defroster conduits on one wing intercommunicating at the outer ends of the wing and terminating at said fuselage, a conduit on said wing for receiving exhaust gasses from the motors, a tail stabilizer on said fuselage, a manifold including a tubular section extending along-side said fuselage beneath said wing with an open front end for taking in air when the airplane is in flight and having a rear discharge end opening onto said stabilizer, said manifold further including a second tubular section extending over said wing from said exhaust conduit into said first section intermediate the ends of said first section and terminating in said first section in a nozzle in concentric spaced relation to said first section with an open rear end whereby air passing through said first section creates a suction behind said nozzle causing suction in the second section whereby exhaust gasses are drawn through said second section and forced out of said nozzle in jet form to heat the air passing through the first section and force the same out of said discharge end for de-icing said stabilizer, and valve controlled means for bypassing gasses out of said second section into one defroster conduit and from the other defroster conduit back into said second section to thereby defrost said wing.

2. The combination with a motor powered airplane having a fuselage and wings, of a pair of longitudinal defroster conduits on one wing intercommunicating at the outer ends of the wing and terminating at said fuselage, a conduit on said wing for receiving exhaust gasses from the motors, a tail stabilizer on said fuselage, a manifold including a tubular section extending along-side said fuselage beneath said wing with an open front end for taking in air when the airplane is in flight and having a rear discharge end opening onto said stabilizer, said manifold further including a second tubular section extending over said wings from said exhaust conduit into said first section intermediate the ends of said first section and terminating in said first section in a nozzle in concentric spaced relation to said first section with an open rear end whereby air passing through said first section creates a suction behind said nozzle causing suction in the second section whereby exhaust gasses are drawn through said second section and forced out of said nozzle in jet form to heat the air passing through the first section and force the same out of said discharge end for de-icing said stabilizer, and valve controlled means for bypassing gasses out of said second section into one defroster conduit and from the other defroster conduit back into said second section to thereby defrost said wing, said first section being provided with means in the rear of said nozzle for directing the heated air out of the same away from said stabilizer when de-icing of the stabilizer is not desired.

3. A manifold for use with a source of hot gas to convey the same from said source for heating purposes, said manifold comprising a straight tubular section for passing air therethrough and having open intake and discharge ends, a second

tubular section for passing hot gas therethrough having an end spaced to one side of the first section for connection to said source, said second section inclining into the first section intermediate the ends of the first section and terminating in said first section in a nozzle spaced from and concentric to said first section whereby gas passing through said second section and out of said nozzle creates a suction in said first section around said nozzle to draw air into the intake end of said first section to be heated by the hot gas issuing from said nozzle and forced out of the discharge end of said first section for use for heating purposes, and valve controlled means for said first section adjacent the discharge end thereof for passing the heated air out of said first section to atmosphere before it reaches the discharge end to thereby control discharge out of said discharge end.
